UNITED STATES PATENT OFFICE

91,541

DESIGN FOR A KITCHEN UTILITY CABINET

Henry W. Pedersen, Berwyn, Ill.

Application May 3, 1933. Serial No. 47,971

Term of patent 14 years

To all whom it may concern:

Be it known that I, HENRY W. PEDERSEN, a citizen of the United States, residing in Berwyn, in the county of Cook and State of Illinois, have invented a new, original, and ornamental Design for a Kitchen Utility Cabinet, of which the following is a specification, reference being had to the accompanying drawing, forming a part thereof:

Fig. 1 is a top plan view;
Fig. 2 is a front elevational view; and
Fig. 3 is a perspective view of the article showing my design.

I claim:

The ornamental design for a kitchen utility cabinet as shown.

HENRY W. PEDERSEN.
